UNITED STATES PATENT OFFICE.

LEWIS TEES, OF PHILADELPHIA, PENNSYLVANIA.

IMPROVED IRON-CLAD VESSEL.

Specification forming part of Letters Patent No. 38,771, dated June 2, 1863.

To all whom it may concern:

Be it known that I, LEWIS TEES, of Philadelphia, Pennsylvania, have invented an Improvement in Iron-Clad Vessels; and I do hereby declare the following to be a full, clear, and exact description of the same, reference being had to the accompanying drawing, and to the letters of reference marked thereon.

My invention consists in the peculiar construction, fully described hereinafter, of armor-plated vessels whereby they are enabled to effectually resist the action of rams and at the same time can be used effectively for shattering the vessels of an enemy. Owing to the peculiar construction of the vessel, plating of much less thickness than usual can be used for resisting the action of shot and shell, the vessel being consequently of lighter draft and admitting of being propelled at a greater speed than ordinary iron-clad war-vessels.

In order to enable others skilled in the art to make my invention, I will now proceed to describe the manner of constructing the same.

The figure in the annexed drawing, which forms a part of this specification, represents a transverse section of sufficient of an iron-clad vessel to illustrate my improvement.

A represents a portion of the spar-deck of the vessel, B being the gun-deck, C the berth-deck, and D the ribs. From the point *a* on the spar-deck to the point *b* the vessel has an inclination similar or nearly similar to that shown in the drawing, and from the point *b* to the point *d*, the latter being about two feet below the water-line, the side of the vessel is partly inclined and partly concave, as represented, or it may be entirely concave between the two points.

The point *b* coincides with a horizontal line drawn midway or thereabout between the upper surface of the gun-deck B and the under side of the beams of the same deck, for a purpose described hereinafter, the breadth of the vessel being greatest at this line.

Massive angular bars, E, of wrought-iron, are secured by means of suitable bolts to this most prominent edge of the vessel, the bars being extended entirely round the vessel, and being tipped with steel, which is properly tempered and reduced to a sharp cutting-edge, *b*.

From the point *a*, which coincides with the edge of the spar-deck, to the steel edge *b*, and from this edge to the point *d*, the vessel is covered with wrought-iron plates three inches

thick, the spar-deck being covered with plates about one inch in thickness.

It should be understood that the frame of the vessel is properly strengthened by knees, stays, braces, &c., which it has not been deemed necessary to illustrate in the drawing.

The advantage of the prominent steel-tipped edge extending round the vessel is that it permits the vessel to be used as a most formidable ram against an enemy's war-ships, and is itself ram-proof, as no ordinary vessel could strike the angular steel-tipped edge without being fatally shattered. The position of the deck B, in respect to the sharp edge *b*, is such that any object striking this edge must be resisted by the deck, which is so intimately and securely connected to other parts of the vessel that the shock is transmitted throughout and absorbed by the entire structure.

It will be seen that at no one point throughout the vessel is a flat surface presented for resisting the direct action of shot or shell, which must necessarily glance off, whether the vessel be struck at points above or below the prominent steel-tipped edge *b*. Much lighter defensive armor can therefore be used than is requisite for vessels having perpendicular sides, or sides varying but slightly from the perpendicular, as in some of the recently-constructed iron-clad ships.

It will be evident that my improved vessels, having a less weight of armor to carry, can be made of lighter draft, can be propelled at a greater speed, and can be made more seaworthy than ordinary plated vessels.

Although I have illustrated the frame of the vessel as made of wood, the ribs and deck-beams, in fact the entire structure, may be made of iron.

I claim as my invention, and desire to secure by Letters Patent—

The combination of the prominent steel-tipped edge *b*, the inclined portion of the vessel from the said edge to the spar-deck A, and the inclined or curved portion from the edge *b* to a point below the water-line, the whole being arranged in respect to the gun-deck B as set forth, for the purpose specified.

In testimony whereof I have signed my name to this specification in the presence of two subscribing witnesses.

Witnesses:

JOHN CLOUDS,
I. R. DEACON,

LEWIS TEES.
